(57) CLAIM

We claim the ornamental design for a cosmetic brush, as shown and described.

DESCRIPTION

FIG. 1 is a top plan view of a cosmetic brush, showing our new design;

FIG. 2 is a side elevational view thereof, the opposite side view being a mirror image; and,

FIG. 3 is a perspective view thereof.

1 Claim, 2 Drawing Sheets

Matter enclosed in heavy brackets [ ] appears in the original patent, but forms no part of this reissue; matter printed in italics indicates the additions made by reissue.

FIG. 1

FIG. 3
